UNITED STATES PATENT OFFICE

HARRY M. ROBERTSON, OF CLEVELAND, OHIO

KILN

Application filed September 7, 1929. Serial No. 391,024.

This invention relates to a kiln of the continuous type.

One object of the invention is to provide an improved kiln having a primary heating chamber or zone and a source of heat therefor so constructed and arranged that heat is applied above and below the ware support to insure efficient and more uniform burning of the ware and less waste thereof due to over-burning or under-burning.

Another object of the invention is to provide an improved continuous kiln through which the ware, disposed on overhanging supports, is conveyed and in which the heating means comprise electric heating units so arranged that heat is supplied both below and above the overhanging portions of the ware supports.

Another object of the invention is to provide an improved continuous kiln having a primary heating chamber the side and top walls of which are arranged and correlated to insure a more uniform circulation and distribution of the heat, both the heat supplied by the heating means and the heat radiating from the walls of the chamber, upon and through the ware, whereby less waste due to over-burning and under-burning of the ware results.

Other objects of the invention will be apparent to those skilled in the art to which my invention relates from the following description taken in connection with the accompanying drawings, wherein

Figs. 1 and 2 taken together constitute a longitudinal section on the line 1—1 of Fig. 3 of a kiln embodying my invention.

Fig. 3 is a fragmentary section on the line 3—3 of Figs. 1 and 4 enlarged.

Fig. 4 is a fragmentary section on the line 1—1 of Fig. 3, enlarged, the ware conveyors being omitted.

Fig. 5 is fragmentary section on the line 5—5 of Fig. 3.

In the drawings, 1 indicates as an entirety a structure having a secondary or preliminary heating chamber or zone 2, a primary heating chamber or zone 2', an annealing chamber 3 and a cooling chamber or zone 4 disposed in connected end to end relation and

forming a continuous kiln through which ware supports 5 move, these supports being mounted on wheeled conveyors or trucks 6 adapted to travel on suitable tracks 7. As shown, the tracks 7 are below the structure 1 and the trucks 6 have portions 8 extending upwardly through an opening 1a formed in and extending throughout the length of the bottom 1b of the structure 1 to mount the supports 5 above or in spaced relation to the lower portion of the chambers 2, 2', 3 and 4 for movement therethrough. This form of construction forms the subject-matter of my co-pending application Ser. No. 320,175; for which reason claims to the broader aspects of the invention are made in said application; whereas this application relates to certain improvements in the construction shown in my aforesaid application and is therefore a continuation in part thereof.

The supports 5 are not shown in detail as the same may be and are preferably constructed substantially according to the supports described and claimed in my co-pending application Ser. No. 357,742 which has become Patent 1,832,818, for which reason no claim to the supports is made herein, except in connection with the improvements herein disclosed.

The heating chamber 2' comprises downwardly inclined side walls 9 terminating at spaced points below the overhanging or cantilever portions of the supports 5, to form the longitudinal opening 1a, already referred to, and an arch 10 extending between the upper ends of the side walls 9. Each of these walls consists of an inner section of suitable refractory material 11 and an outer section of suitable insulating material 12. The inner sections 11 of the side walls 9 rest on longitudinal sills 13, also formed of suitable refractory material. The lower face of each sill 13 is provided with a shoulder 14 which engages a complementary wall on a base member 15 and the base member is seated against the vertical flange 16 of an angle 17 anchored, as will later appear. Where the tracks 7 are to be substantially on the level of the surface, the structure 1 is supported by a frame work 18 consisting of spaced I-beams 19 resting on 100

the flooring 20, pairs of outer uprights 21 mounted on the beams 19, pairs of inner uprights 22 also mounted on the beams 19 and supporting sills 22a and I-beams 20a connected in any desired manner at their outer ends to the uprights 21 and resting on their inner portions on the sills 22a. The various elements of the frame-work 18 may be secured to each other in any well known manner. The upper ends of the uprights 21 are preferably connected by tie-rods 23. 24 indicates a sheathing for the side walls 9. This sheathing preferably comprises steel plates arranged edge to edge and having a vertical portion 24a engaging the uprights 21, an inclined portion 24b and a horizontal portion 24c resting on the beams 20a. The horizontal flanges of the angles 17 are suitable secured to the free edges of the portions 24c. As shown, the insulating material extends over the horizontal portion 24c of the sheathing and below the base member 15. The sheathing 24 serves as a support for the materials when the walls are being constructed and also protects these walls to prevent their deterioration. Each of the vertical portions 24a has secured to its inner surface an angle 25, which forms a seat for the outer sides of blocks 26 extending from end to end of the heating chamber, the inner sides of the blocks resting on the upper end of the inner wall section 11 of the adjacent side wall 9. The blocks 26 serve as lateral abutments for key members 27 which rest on the side wall sections 11 and form supports for the opposite end walls of arch 10. The upper ends of the plates are extended upwardly and bent to form inclined supports 24' to which reference will later be made.

40 The opposed side faces of the opening 1a have pairs of inwardly projecting ribs 28, preferably extending continuously throughout the heating chamber 3. The ribs on each face are in spaced relation and disposed above and below and overlap a longitudinally extending rib 29 projecting outwardly from the adjacent face of each truck portion 8, these correlated ribs serving to prevent the escape of heat and intake of air with resulting loss of heating efficiency.

45 The walls forming the chambers 2 and 3 are preferably constructed in a similar manner to the main heating chamber 2', as above described, except that the insulating walls for the annealing chamber 3 may be omitted, if desired. At its outer end the preheating chamber is connected with an elongated supply chamber 30 preferably similar in construction to the chambers 2, 2' and 3, except that its roof 31 is preferably horizontal so as to be in relatively close relation to the load on the supports 5, thereby preventing inflow of air into the preheating chamber.

50 32 indicates a damper controlled, exhaust flue leading through the roof or arch 10 for

the preheating chamber, this flue being disposed at or adjacent the outer end of the chamber 2. The outer or discharge end of the flue 32 may be connected to a power driven suction creating device (not shown), the effect of which is to induce a flow of the heat supplied to or within the heating chamber 2' through the preheating chamber 2 in a direction opposite to the direction of movement of the ware supports, whereby the latter and the ware carried thereby are gradually heated to a relatively high temperature before entering the chamber 3.

55 The cooling chamber 4 is connected in end to end relation to the outer end of the annealing chamber 3 as already set forth. The roof for the chamber 4 preferably consists of a manifold 33 extending from end to end thereof. The manifold has at its outer end an inlet opening 33a connected to a conduit 34 through which air flows to the manifold. The inner end of the manifold has an outlet 33b connected to a discharge conduit 35. The conduit 35 is provided with a power driven suction fan which induces a flow of air through the manifold 33. The bottom wall of the manifold is preferably horizontal and disposed in close parallel relation to the ware on the supports 5 as the latter moves to the discharge opening.

60 37 indicates as an entirety the heat supply means for the chamber 2'. The means 37 comprise pairs of electric heating elements 38, 38a, disposed along each wall 9 and supported in parallel relation thereto and a connector 39 between the elements of each pair to connect them in series. The elements comprise rods of suitable resistance material and each connector 39 consists of a plate of conducting material countersunk in an up-standing portion 13a of the blocks 13. As shown each plate 39 is formed with a pair of recesses which receive the lower ends of a pair of rods 38, 38a. The upper ends of the rods fit into collars 40 preferably formed of suitable insulating material.

65 The collars 40 are countersunk in the key members 27 and their openings register with openings 41 extending through the key members 27 and insulating wall 12, these openings being preferably lined with sleeves 41a. 42 indicate conductors extending through the sleeves 41a and into the collars 40 and each making contact with the adjacent element 38 or 38a. The upper end of each conductor 42 is provided with a mounting which includes an arm 43 having a bifurcated outer end. 44 indicates angles secured to the adjacent support 24' in any desired manner. Each angle is formed with an opening in which is mounted a bolt 45 extending through the bifurcations of the adjacent arm 43. Provided on each bolt 45 is a washer 46 and a nut (such as a thumb nut) 47. Between the washer 46 and arm 43 and coiled around the

bolt is a spring 48, these parts being so arranged and related that upon tightening of the nut 47, the spring 48 acting through the arm 43 will maintain the adjacent conductor 42 in yielding contact with the adjacent element 38 or 38a. The mounting for each conductor is provided with a threaded shank 49 carrying two nuts 50 between which one end of a lead 51 is clamped, the other end of the lead being connected to one supply main 52. As shown in Fig. 5, one element 38 is connected to one main 52 and the other element 38a is connected to the other main 52, so that each pair of elements and its connector 39 forms a complete circuit.

Suitable switch means are provided for controlling the supply of current through the mains 52. The mains may be carried through a pipe 53 of insulating material, mounted on an angle 54, which is supported by the uprights 21.

In my construction of kiln it will be noted that the resistance elements are supported close to and in parallel relation to the side walls 9. This arrangement permits the inner sections of the walls to absorb heat, which is radiated therefrom. As these side walls are inclined upwardly the radiant heat is projected upwardly into the space below the arch 10 and as the latter is curved in symmetrical relation to the moving ware, the heat radiating from the latter is directed downwardly thereupon to effect its burning. By this arrangement of walls, the heat resulting from the resistance rods or elements circulates and radiates into the space substantially centrally of the walls 9, 9, 10, so that a large volume of air heated to the desired temperature is provided in the chamber 2' and serves to effect burning of the ware in an economical manner.

The trucks 6 are moved step by step by means of a thrust member 54 which is reciprocated by a suitable mechanism 55. The member 54 is arranged to engage a truck 6 and move it endwise on the track 7 and this truck moves those in front of it, the trucks being moved in this manner at predetermined intervals, a loaded truck being placed in line at the entrance prior to each operation of the thrust member. The trucks at the discharge end are rolled onto a transfer truck and unloaded and again brought into position at the entrance and loaded.

Furthermore, it will be noted that by inclining the side walls 9 of the heating chamber and the resistance rods, they may and preferably do extend downwardly beyond the supports 5 and also below and within their lateral, overhanging or cantilever portions. This insures the application of heat below the supports 5 and between the legs 5a thereof, so that a large volume of heated air and radiant heat may pass around the ware; it also insures the application of heat

to the supports 5 so that the latter absorb heat which is conducted to the ware.

The heating means may consist of any desired number of heating elements and the current supply may be regulated to provide any desired temperature in the chamber 2'. In the arrangement shown I prefer to subject the ware to a temperature approximating 1500 degrees F. The ware to be treated may be formed of ceramic materials, but ware formed of other materials may be passed through the kiln for treatment.

To those skilled in the art to which my invention relates, many changes in construction and widely differing embodiments and applications of my invention will suggest themselves without departing from the spirit and scope thereof. My disclosures and the descriptions herein are purely illustrative and are not intended to be in any sense limiting.

What I claim is:

1. In apparatus of the class described, the combination of a preliminary heating chamber, a main heating chamber connected in end to end relation with said preliminary heating chamber to form a continuous kiln, the side walls of said main heating chamber converging downwardly and spaced at their lower ends to form an opening in line with an opening formed in the lower portion of said preliminary heating chamber, conveying means having portions extending upwardly through the openings in said chambers and movable therethrough and carrying ware supports within said chambers, said conveying portions extending upwardly so as to carry said supports in spaced relation to the lower ends of said converging walls, and electric heating units disposed upon one of said converging walls of said main heating chamber and extending to a point below and inwardly of the lateral side portions of said ware supports.

2. In apparatus of the class described, the combination of a preliminary heating chamber, a main heating chamber, the side walls of said main heating chamber converging downwardly and spaced at their lower ends to form an opening in line with an opening formed in the lower portion of said preliminary heating chamber, conveying means below said chambers and having portions extending upwardly through said openings and movable from end to end thereof, ware supports carried by the upper ends of said conveying portions and having lateral portions disposed in spaced relation to and overhanging the lower ends of said converging walls, and heating means adjacent one of said converging walls and arranged to supply heat above and below said ware supports.

3. In apparatus of the class described, the combination of a preliminary heating chamber, a main heating chamber, the side walls of said main heating chamber converging

- downwardly and spaced at their lower ends to form an opening in line with an opening formed in the lower portion of said preliminary heating chamber, conveying means below said chambers and having portions extending upwardly through said openings and movable from end to end thereof, ware supports carried by the upper ends of said conveying portions and having lateral portions disposed in spaced relation to and overhanging the lower ends of said converging walls, and heating means adjacent one of said converging walls, said heating means comprising electrical heating units disposed in spaced relation to said converging wall and extending from a point above to a point below the ware supports.
4. In apparatus of the class described, the combination of a preliminary heating chamber, a main heating chamber, the side walls of said main heating chamber converging downwardly and spaced at their lower ends to form an opening in line with an opening formed in the lower portion of said preliminary heating chamber and connected at their upper ends by an arch roof, conveying means below said chambers and having portions extending upwardly through said openings and movable from end to end thereof, ware supports carried by the upper ends of said conveying portions and having lateral portions disposed in spaced relation to and overhanging the lower ends of said converging walls, and heating means adjacent one of said converging walls and arranged to supply heat above and below said ware supports, said heating means comprising electrical heating units disposed in spaced relation to one of said converging walls and extending in vertical planes from the roof to a point below the adjacent lateral portions of said ware supports.

In testimony whereof, I have hereunto signed my name.

45 HARRY M. ROBERTSON.
